UNITED STATES PATENT OFFICE.

SHERMAN TAYLOR, OF WYMORE, NEBRASKA.

DOOR.

1,426,424.

Specification of Letters Patent. Patented Aug. 22, 1922.

Application filed March 14, 1921. Serial No. 452,054.

To all whom it may concern:

Be it known that I, SHERMAN TAYLOR, a citizen of the United States, residing at Wymore, in the county of Gage and State 5 of Nebraska, have invented a new and useful Door, of which the following is a specification.

This invention relates to doors primarily designed for use in connection with doors 10 of vaults and the like although it is to be understood that the improvement can be applied to various kinds of doors.

One of the objects of the invention is to provide a door with a combined sight and 15 ventilating opening which is normally closed by a plug, this plug being removable solely by a person behind the door so that should said person be locked within a vault it becomes possible for him to remove the plug 20 and thus not only secure the necessary fresh air but also gives him a view of the exterior surroundings.

A further object is to provide a plug or 25 closure the outer face of which is flush with the corresponding face of the door so that said plug is not noticeable from the outside.

A still further object is to provide simple 30 and efficient means for fastening the plug in place so that it cannot be removed except by pressure from back of the door.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the 40 invention shown can be made without departing from the spirit of the invention.

In the accompanying drawings the preferred form of the invention has been shown.

In said drawings

45 Figure 1 is an elevation of a portion of the back face of a door and showing the present improvements combined therewith.

Figure 2 is a section on line 2-2, Figure 1.

50 Referring to the figures by characters of reference 1 designates a portion of a door in which is provided an opening 2 which is frusto-conical, the said opening tapering toward the back or inner face of the door.

In this opening is removably seated a plug 3 55 the outer end of which lies flush with the outer surface of the door and can be finished so as to correspond therewith and not be noticeable from without. The inner end of the plug is provided with an extension 4 60 having an annular groove 5 and this groove is adapted to receive opposed walls of a key hole slot 6 which is formed in a locking plate 7. Said plate is adapted to bear against the back face of the door 1 and 65 when in engagement with the extension 4 will obviously hold the plug 3 securely in position.

Should a person be locked in a vault either accidentally or otherwise it is possible for 70 him to push the plate 7 upwardly and remove it from the extension 4. By then pounding on said extension the plug 3 will be dislodged and will fall outwardly from the opening 2. Thus fresh air can pass 75 into the vault and at the same time the occupant of the vault will have a view of the area in front of the vault. The opening also constitutes a loop hole through which the occupant of the vault can fire at burglars 80 who may have closed the door.

What is claimed is:—

1. The combination with a door having an inwardly tapered opening therein, of a tapered plug normally seated in the opening and having an extension at its small end projecting from the back or inner face of the door, and means engaging said extension for holding the plug against withdrawal from the opening. 90

2. The combination with a door having an inwardly tapered opening therein, of a frusto-conical plug removably seated within the opening and having its large face flush with the outer face of the door, an extension upon the small end of the plug having an annular groove, and means detachably seated by gravity in the groove for holding the plug against removal from the opening. 100

In testimony that I claim the foregoing as my own, I have hereto affixed my signature in the presence of two witnesses.

SHERMAN TAYLOR.

Witnesses:

SHERMAN TAYLOR, JR.,
B. O. YOULL.
